TO EVERHOT HEATER COMPANY, OF DETROIT, MICHIGAN, A CORPORATION OF
MICHIGAN.

GAS BURNER.

Application filed March 1, 1926. Serial No. 91,596.

The invention relates to gas burners and more particularly to a construction designed for use with normal gas pressures ranging in different localities from two or three inches 5 of water to as much as thirty inches and adapted for thermostatic control, whereby the flame may be turned up or down to regulate the flow of gas from the minimum required for a pilot light, to the maximum for 10 heating effect.

One of the objects of the invention is to provide a burner construction of the above type which is quiet in operation at all demands avoiding the noises that have heretofore been associated with such burners. Another object is to provide a construction 15 capable of being used either with manufactured or natural gas at the pressures found in various localities without danger of extinguishing the flame. A further object is to shorten and spread the flame so that complete combustion can be effected in a shorter space, thereby enabling the burner to be set closer to the device to be heated.

25 Our burner is particularly adapted for use in connection with a water heating apparatus of the type which always has a supply of hot water available for use, the burner being controlled thermostatically according to the 30 demand. In the present state of the art it is common to direct the mixture from two or more burner tubes toward each other to cause an impingement of the flames but this construction when operated at maximum demands causes a roaring noise which may be 35 heard at a considerable distance from the burner. Our improved construction has all the advantages of the impinging type of burner and has further advantage of a practically noiseless operation, more complete 40 combustion and shortening of the space required for combustion.

In general, our burner comprises one or 45 more mixing tubes of a modified Bunsen burner type capable of being operated both as a pilot light and as a powerful burner and being so constructed that if the flame burns within the tube at low demands, it will be expelled outward at higher demands. 50 Spaced from each mixing tube and in alignment therewith is a solid baffle, preferably metallic, against which the gases strike and are deflected and spread, thus exposing a larger surface to the air. The baffle is pref-

erably curved to form a smooth surface 55 adapted to change the direction of the flame without causing turbulence of the burning gases. The distance of the baffle from the outlet of the mixing tube is preferably made as short as possible consistent with the securing of proper combustion of the gases. When our burner is used with manufactured 60 gas which has a relatively high rate of flame propagation, the gases will ordinarily burn throughout the entire distance between the outlet of the mixing tube and the baffle even when the burner is operating under maximum demand, but when the burner is used with natural gas having a lower rate of 65 flame propagation, the gases will at certain stages burn at the baffle only. If the mixing tubes were not provided with baffles and the burner operated with natural gas, there would be a danger of the flame being lifted off to the point of extinction. If on the other hand the burner tube were placed 70 so close to the surface to be heated as to prevent the lifting of the flame then the flame would result in the deposition of carbon 75 upon the heating surface due to the flame striking a relatively cold surface. Our construction therefore insures the maintenance of the flame when operating with natural gas and at the same time shortens the space required for combustion and eliminates all 80 danger of carbon deposits.

In the drawings:

Figure 1 is a sectional elevation of a hot water heater embodying our invention.

Figure 2 is a plan view of the burner.

Figure 3 is a transverse section on the line 3—3 of the Figure 2.

Figure 4 is a section on the line 4—4 of Figure 2.

Figure 5 is a perspective view of a modified construction.

Figure 6 is a longitudinal section of the valves of Figure 1.

Referring now more specifically to the embodiment of the invention illustrated in Figures 1 to 4, A is the hot water tank, B the gas supply conduit, C the thermostatically controlled throttle valve for the gas supply and D the improved burner. The tank A is preferably surrounded by an insulating jacket E spaced from the sides of the tank to form a surrounding flue E' for the products of the combustion from the

burner. This jacket is continued downwardly below the bottom of the tank A forming a combustion chamber F and the burner D is arranged in the combustion chamber 5 centrally below the tank A and spaced from the same.

The burner comprises a central head G having a threaded inlet opening G', adapted to be attached to the end of the gas supply conduit B. The upper portion of the head is preferably polygonal in shape, each side being provided with a threaded aperture H, for receiving a correspondingly threaded burner tube I. Each of the burner 10 tubes extend radially outward from the burner head and while any desired number of tubes may be employed, the construction as specifically illustrated is provided with four tubes arranged 90° apart. Each burner is 15 constructed with a central calibrated gas orifice J and with one or more air inlet apertures K extending through the cylindrical walls of the tube on the discharge side of the gas orifice J. The gas and air inlet orifices are so proportioned that under maximum supply only a portion of the oxygen required for complete combustion is co-mingled with the gas in the tube. This has the 20 effect of making an over-rich gas mixture and decreasing the rate of flame propagation, so that the velocity of the mixture in the tube will expel the flame and compel the mixture to burn entirely outside of the burner tube. When such a tube is operated under minimum requirement that is, when only sufficient gas is supplied to maintain a pilot 25 light there is a possibility that the flame will ignite back within the burner tube, but as soon as the velocity is increased to beyond 30 the speed of flame propagation the flame will pass outward and burn entirely outside of the burner tube.

L represents the baffle member which is sleeved upon the lower portion of the burner head G and secured thereto by suitable means, such as a set screw L'. This baffle has the radially extending arms M arranged below each of the burner tubes I and as shown the arms are all part of a single 45 integral casting. At the outer end of each arm the baffle is curved upwardly as indicated at N crossing the path of the gases issuing from the adjacent burner tube. The portion N is preferably gradually curved 50 from a direction parallel to the burner tube, to a direction transverse thereto, thus providing a smooth deflecting surface against which the burning gases impinge. Each of the arms M is preferably provided with a 55 cut away portion O of substantially triangular shape, arranged directly below the outlet of the burner tube in order to facilitate the mixture of air with the burner gases 60 and to prevent accumulations of foreign 65 matter around the outlets of burner tubes.

The arms N are also preferably constructed with relatively thin walls which are reinforced by a series of ribs P to insure adequate strength of the casting.

In order that the gas burner as above described may be used in various localities where the gas available for heating purposes is supplied under varying pressures, each burner head G is provided with a removable plug Q having a calibrated orifice Q' 70 therein, adapted to supply all of the gas for the several burner tubes. A series of exchangeable plugs is provided having orifices of different calibrations so that in any particular locality the burner head may be fitted with the one which will insure a certain predetermined pressure within the burner head. Thus the burner tubes I may be constructed to have the gas and air orifices J and K respectively, proportioned to give 75 the desired mixture with a predetermined gas pressure and this pressure may be secured in the burner head regardless of the pressure commercially obtainable in a particular locality by the selection of the 80 proper calibrated plug Q.

The position of the calibrated plug in the supply line is not of great importance as far as the functioning of the burner is concerned, except that it must not be too close 85 to the burner tubes, as in that event the discharge through the calibrated orifice causes turbulence interfering with the proper distribution of the gas into the burner tubes and increasing the noise of operation. Therefore in the construction as illustrated in Figure 3 the burner head G is of sufficient length so that when the plug Q is in position it will be spaced far enough from the burner tubes to prevent turbulence and 90 noise. However, the regulating orifice may conveniently be placed further from the burner head with equally good results and in Figure 1 the supply pipe B is provided with the calibrated orifice W in the shut off valve W', the latter being located on the inlet side of the throttling valve C. The use 95 of the calibrated plug in either position is of particular value in burners operating on natural gas, for by reducing the pressure 100 before entering the burner tubes the noise of the burner is greatly reduced.

In the operation of the burner as above described the mixture formed in the various burner tubes emerges from the burner head in a radial direction, but the flames are all deflected upwardly by the curved baffles N, so as to be directed against the bottom of the water tank A. Such a construction results 105 in obtaining the advantages heretofore mentioned and is a marked improvement over burner constructions heretofore employed in hot water heaters.

In the modification as illustrated in Figure 5, the burner comprises the parallel 110

tubes R and R' connected together at one end and provided with a central gas supply conduit R². The parallel portions R and R' are each provided with a plurality of 5 burner tubes I similar to those previously described, but in this case the burner tubes are all arranged parallel to each other in a direction extending toward the water tank. In order to shorten the flame and prevent the 10 extinguishment of the same under certain conditions, each burner tube is provided with a circular baffle plate S, arranged in alignment with the same. These baffles may be suitably connected to the burner and as 15 shown there are the connecting bars T and T' arranged parallel to the tubes R and R' respectively, and supported by a cross bar U, which in turn is mounted on a vertical rod U' rising from a cross bracket U². The 20 bar U' is preferably threaded to provide for a vertical adjustment of the baffles S, with respect to the burner tubes.

With the modified arrangement as above described, the gases from the burner tubes 25 impinge directly upon the baffles S and are thereby spread out to expose a larger surface to the air. This results in complete combustion in a shorter space and eliminates the necessity of causing the flames from two 30 jets to impinge upon each other as in the usual burner constructions.

What we claim as our invention is:

1. In a gas burner, the combination with a burner head having a plurality of radially 35 extending mixing tubes arranged substantially in a common plane, a series of baffles each being spaced from the outlet of one tube and arranged in the path of the issuing mixture, said baffles having curved imperforate surfaces extending outwardly and transversely of said tubes, thereby deflecting the flames from all of said tubes in the same direction substantially perpendicular to said plane.
2. In a gas burner, the combination with a burner head, having a plurality of radially 40 extending mixing tubes arranged substantially in a common plane, of a member extending radially of said burner head at one 45 side of said plane, said member having a series of curved imperforate baffle surfaces

opposite the respective tubes adapted to deflect the flames therefrom in a direction transverse to said plane.

3. In a gas burner, the combination with a 5 burner head, of a series of mixing tubes extending radially of said head, a series of radially projecting members arranged below said tubes, each member having a curved surface extending across the path of the 60 mixture from the adjacent tube and having a cut-away portion immediately below the outlet of said tube.

4. In a gas burner, the combination with a central gas supply conduit, of a burner 65 head mounted thereon, a series of mixing tubes extending radially of said head in a horizontal plane, and a member connected to said burner head below said tubes having imperforate portions crossing the path of 70 each of said tubes, said crossing portions being spaced from said tubes and being gradually curved from the horizontal to the vertical.

5. A gas burner comprising a central 75 gas supply head, a plurality of burner tubes extending radially outward from said head, each tube having gas and air inlet ports proportioned to produce a rich mixture in said tube having a low rate of flame propagation such that said tube will be swept free from all flame at mixture velocities obtainable under normal gas pressures, a member having a hub secured to said gas supply head, said member having a series of integral 80 baffles extending radially outward from said hub each baffle being arranged opposite a burner tube and having a cut-away portion adjacent said tube for introducing air to the mixture impinging on the baffle, each baffle 85 having a surface extending at an angle to the path of the discharged mixture and of an area sufficient to intercept and deflect all of the mixture issuing from the co-operating burner tube whereby complete 90 combustion of the mixture is obtained in a short distance.

In testimony whereof we affix our signatures.
